UNITED STATES PATENT OFFICE.

ELEAZAR T. WILKINSON, OF PHILADELPHIA, PENNSYLVANIA, ASSIGNOR TO DAVID LUPTON'S SONS COMPANY, OF PHILADELPHIA, PENNSYLVANIA, A CORPORATION OF PENNSYLVANIA.

RETAINING DEVICE FOR WINDOW-PANES.

1,023,479.

Specification of Letters Patent.

Patented Apr. 16, 1912.

Application filed June 19, 1911. Serial No. 633,932.

To all whom it may concern:

Be it known that I, ELEAZAR T. WILKINSON, of Philadelphia, in the county of Philadelphia and State of Pennsylvania, have 5 invented certain new and useful Improvements in Retaining Devices for Window-Panes, whereof the following is a specification, reference being had to the accompanying drawings.

10 My invention relates to a device intended to take the place of putty or cement as a means of retaining a pane of glass in place in the sash bars. My invention is applicable to window frames with sash bars of any 15 ordinary description, but it may very conveniently be employed in connection with metal sash bars.

My invention consists of a metal strip of L-shaped cross section with adjustable means 20 for causing it to crowd against or pinch the pane between itself and the molding of the sash bar at whatever point along the edge of the pane the fastening device is placed.

In the accompanying drawings, Figure I, 25 is a plan view illustrating a portion of a sash with a pane held in place by the use of my improvement. Fig. II, is a partial section along the line II, II of Fig. I, on an enlarged scale. Fig. III, is a section along 30 the line III, III, of Fig. II. Fig. IV, is a perspective view of my fastening device.

The fastening device consists of a metallic strip of convenient length and of L-shaped cross section. It may therefore be 35 conveniently spoken of as comprising a wall 1, and a flange 2. The wall 1, projects beyond the flange in the form of lugs 3, 4, 3. These may be either terminal lugs as shown 40 at 3, 3, or intermediate lugs 4, conveniently interposed at intervals and formed by making a partial cut 5, at the inner corner of the flange and turning the expanded piece of metal down. An inclined slot 6, is also cut 45 in the wall 1. Pins 7, are passed through and secured within the tongues of the sash

bars at proper points or intervals where it is desired to secure the fastening device.

In operation, the panes 10, are laid so as to rest against the inner edges of the molding 11, of the sash bar as usual. One of the 50 fastening devices is then laid with its wall against the side of the tongue of the sash bar and with its flange pressing against the pane near its edge, the lugs 3, 4, 3, being inserted between the edge of the pane and 55 the tongue of the sash bar. In this position the pin 7, enters the slot 6, in the wall of the fastening device and by driving the fastening device in such direction as to cause the pin to press against the inclined 60 edge of the slot 6, which receives it, the required degree of pressure is exerted by the retaining device to hold the pane firmly in position against the inner surface of the molding of the sash bar. 65

It is obvious that my device may be made of varying lengths as circumstances may dictate, and may be likewise spaced at any desired intervals along the edge of the pane. For a small pane, ordinarily one will suffice 70 for each edge.

Having thus described my invention, I claim:

A device for holding a pane within its sash bars, consisting of a metal strip of L- 75 shaped cross section, one wall of the same being provided with an inclined slot and with lugs which project below the corner formed with the other wall, and a pin projecting from the surface of the tongue of 80 the sash bar and received within said inclined slot.

In testimony whereof, I have hereunto signed my name at Philadelphia, Pennsylvania, this fourteenth day of June, 1911.

ELEAZAR T. WILKINSON.

Witnesses:

JAMES H. BELL,
E. L. FULLERTON.
